United States Patent Office.

ANDREW H. SCHOLFIELD AND DE WITT C. STERRY, OF WORCESTER, MASSACHUSETTS.

Letters Patent No. 79,150, dated June 23, 1868.

IMPROVEMENT IN PUMPS.

The Schedule referred to in these Letters Patent and making part of the same.

TO ALL WHOM IT MAY CONCERN:

Be it known that we, ANDREW H. SCHOLFIELD and DE WITT C. STERRY, of Worcester, in the county of Worcester, and State of Massachusetts, have invented a new and useful Machine for the Raising of Water from Wells, Cisterns, &c.; and we do hereby declare that the following is a full, clear, and exact description of the construction and operation of the same, reference being had to the annexed drawings, making a part of this specification, in which—

Figure 1 is a perspective view.

Figure 2 is an interior view of one-half of fig. 1, and

Figure 3 a view of the conductor as detached.

A A represent a cylinder.

B B represent the head of the cylinder.

C C represent openings or inlets for the water.

D D represent valves connected with inlets.

E E represent ring holding the head in place.

F F represent flange of conducting-pipe.

G G represent lower section of pipe, movable.

H H represent upper section of pipe, stationary.

I I represent stuffing-box.

J J represent spur-wheel, crank, and chain for raising or lowering the lower section of conductor.

We construct a cylinder, A A, of any required dimensions, of any suitable material, as iron, copper, clay, wood, and with or without bottom. This cylinder is placed in the well, cistern, or reservoir, as the case may be. It rests upon the bottom of the well, and actual experiment demonstrates that it will work with ease and certainty, even though the water should cover it several feet. To the interior surface of the cylinder, at a point midway its length, is fastened the mouth of an inverted flexible cup or diaphragm, B B. It is made of any suitable water-tight or workable material, such as vulcanized rubber, reference being had to its healthfulness, purity, and durability. This cup or head is held in its place by a close-fitting ring, E E, so that it is impossible for any water to escape between it and the face of cylinder. At its apex the head is pierced to receive a conducting-pipe, S. This is secured to the head by flanges F F, which also prevent any leakage around the entrance of the pipe. This lower pipe is of iron, and at a suitable point enters, through a stuffing-box, I I, the upper section H H, which is stationary, while the lower pipe plays up and down, being regulated by the spur-wheel and its connections. Near the bottom of the cylinder are several openings or inlets C C, through which the circumfluous waters enter the cylinder. These openings are supplied with valves D.

In ordinary cases the cylinder would hold about sixty (60) gallons, (though they can be made of any required capacity.) Two-thirds or thereabouts of the contents would be forced up through the pipe, and discharged by the pressure of the movable section of pipe, its own weight being sufficient ordinarily, but if found insufficient in any given case, may be made all-sufficient by coupling on to the movable pipe a suitable weight.

The spur-wheel and its connections J J, supported by the upper part of the tube, which of course is fixed in position by lateral connections, are designed to let on or take off, as desired, the pressure upon the head. Touching the pawl of the ratchet-wheel, so as to give play to the lower section of the pipe, its weight crowds the water so as at once to shut tight the valves D, and the water imprisoned rushes up and escapes through the pipe with great force, until the cylinder is mainly emptied. Then, by a turn of the ratchet-wheel, the head, (which in drawing a large quantity of water, would be completely inverted,) would be brought back to its natural place, while the circumfluous waters press open the valves, and rushing in, fill the cylinder in a moment, so that an almost unbroken stream of water may be had until the reservoir or cistern is exhausted.

What we claim as our invention, and desire to secure by Letters Patent, is—

The diaphragm-pump, having a hollow rod with telescopic connections, and operating substantially as described.

A. H. SCHOLFIELD,
DE WITT C. STERRY.
